SPEED CONTROL SYSTEM WITH COMPARISON OF A SAWTOOTH WAVE WITH A REFERENCE LEVEL

BACKGROUND OF THE INVENTION

This invention relates to a speed control system for controlling the speed of rotary members such as, for example, a motor, capstan and so on in magnetic recording and reproducing devices, and more particularly to a speed control system which ensures stable and highly sensitive speed control of the rotary members and enables selection of the reference speed of the rotary members over a wide range.

DESCRIPTION OF THE PRIOR ART

Hitherto, various systems have been proposed for controlling the speed of motors and other rotary members. With these prior art systems, however, no satisfactory followup property of control is obtained and, in addition, the rotational speed of the rotary members cannot be freely established at a desired value. Further, the revolving speed control of DC motors encounters a "self-start" problem, as set forth in copending application, U.S. Ser. No. 586,771 assigned to the same assignee as the present application. In addition, the provision of a speed control circuit in the form of an integrated circuit is difficult, since heat generation often leads to breakage of the integrated circuit.

SUMMARY OF THE INVENTION

This invention is directed to a speed control system for rotary members in which a sawtooth wave signal, frequency-modulated in accordance with the speed of the rotary members, is produced; the speed of the rotary members is controlled in response to the sawtooth wave signal; and the inclination of the sawtooth wave is varied to select the speed to be maintained. Consequently, the speed control circuit operates with a pulse signal and hence is low in power consumption and is easy to construct in the form of an integrated circuit. Further, the use of this system in the speed control of DC motors enables self-start of the motors.

The primary object of this invention is to provide a speed control system for rotary members which permits free selection of the speed of the rotary members over a wide range and is excellent in the followup property of speed control.

Other objects, features and advantages of this invention will become apparent from the following description taken in conjunction with the accompanying drawings.

BRIEF DESCRIPTION OF THE DRAWINGS

FIG. 1 is a circuit connection diagram of a rotary member speed control system in accordance with one embodiment of this invention;

FIG. 2 is a series of waveform diagrams for explaining the speed control system exemplified in FIG. 1;

FIG. 3 is a circuit connection diagram showing another embodiment of the present invention system; and

FIG. 4 is a series of waveform diagrams for explaining the speed control system depicted in FIG. 3.

DESCRIPTION OF THE PREFERRED EMBODIMENTS

In FIG. 1 reference numeral 1 designates a signal generator SG which is mounted on a rotary shaft of a motor M and rotates with the rotation of the motor M and from which a signal S_1 is derived such as depicted in FIG. 2A which is frequency-modulated in accordance with the rotational angular velocity of the motor M. The frequency-modulated signal S_1 is fed to a waveform shaping circuit 2 constituted by, for example, an NPN-type transistor Tr_1 . Thus, there is derived from the waveform shaping circuit 2 a rectangular wave signal S_2 such as depicted in FIG. 2B which corresponds to the frequency-modulated signal S_1 . The resulting rectangular wave signal S_2 is applied to a differentiation circuit 3 consisting of a capacitor C_1 and a resistor R_1 to produce differentiated pulses

S_3 and S_4 respectively at the rise and fall of the rectangular wave signal S_2 as shown in FIG. 2C.

The differentiated pulses S_3 and S_4 are fed to a sawtooth wave generator 4 consisting of transistors Tr_2 and Tr_3 to drive the generator 4 with either one of the differentiated pulses S_3 and S_4 , that is, S_3 in the illustrated example, thus providing a sawtooth wave signal S_5 such as shown in FIG. 2D which has a period equal to that of the differentiated pulse S_3 and consequently varies its peak value in accordance with the period.

10 In this case the inclination of the sawtooth wave signal S_5 is rendered variable. Namely, the time constant for charge of the signal S_5 is made variable. In the illustrated example, such variation of the time constant is made possible by connecting the collector of the transistor Tr_2 of the sawtooth wave generator 4 to a movable contact S_F of a changeover switch S which is selectively engageable with one of the switch contacts S_{11} , S_{12} and S_{13} respectively connected to a power source terminal 6a through series circuit R_{10} , R_{20} or R_{30} respectively consisting of resistor R_{11} , R_{21} or R_{31} , and variable resistor R_{12} , R_{22} or R_{32} , and a resistor R_8 .

15 With such an arrangement, changeover of the switch S or adjustment of the variable resistor R_{12} , R_{22} or R_{32} causes a change in the charge time constant thereby to change the inclination of the sawtooth wave signal S_5 . It is also possible, of course, to change the time constant by making variable a capacitor C_4 of the sawtooth wave generator 4, or by selectively changing over a plurality of capacitors which are provided instead of the capacitor C_4 or by rendering the resistance and capacitance values variable.

20 It is preferred, in this case, to improve the linearity of the sawtooth wave signal S_5 by a positive feedback circuit in which the collector output of the transistor Tr_2 is applied to the base of the transistor Tr_3 and the emitter output of the transistor Tr_3 is fed through a capacitor C_3 , the series circuit R_{10} , R_{20} or R_{30} , and the switch S to a collector load circuit of the transistor Tr_2 .

25 The sawtooth wave signal S_5 is applied to the base of a transistor Tr_4 of a differential amplifier circuit consisting of the transistors Tr_4 and Tr_5 of, for example, a comparator circuit 5.

30 The differential amplifier circuit can be constructed by applying to the base of the transistor Tr_5 a reference DC voltage E, produced by dividing the voltage of, for example, the power source terminal 6a with the variable resistor R_2 and the resistors R_3 and R_4 , and by connecting the connection point of the emitters of the transistors Tr_3 and Tr_4 to the other power source terminal 6b through an emitter resistor R_7 .

35 Thus, the sawtooth wave signal S_5 fed to the base of the transistor Tr_4 is compared with the sum E_1 of a voltage, yielded in the emitters of the transistors Tr_4 and Tr_5 by the aforementioned reference DC voltage E fed to the base of the transistor Tr_4 , and a forward drop voltage between the base and emitter of the transistor Tr_4 , thus deriving from, for example, the collector of the transistor Tr_4 a signal S_5' shown in FIG. 2D'.

40 In the differential amplifier circuit it is possible, if necessary, to adjust the amplitude of the signal S_5' by making the aforementioned resistor R_2 variable to thereby render the reference DC voltage E variable. This leads to the variations in the pulse width of a signal S_6 described later and hence enables adjustment of the rotational speed of the motor M.

45 Further, the differential amplifier connection of the transistors Tr_4 and Tr_5 leads to reduction of drift of the rotational speed of the motor which is caused by the influence of the ambient temperature variations on the signal S_5' . The signal S_5' is a triangular wave having a varying peak value and, in order to convert the triangular wave signal S_5' into a width-modulated rectangular wave, the signal S_5' is applied to, for example, the base of an emitter-follower type transistor amplifier consisting of a transistor Tr_6 and is thereby amplified, the amplified output being fed to a pulse width modulator circuit 7.

50 The pulse width modulator circuit 7 is provided with, for example, an NPN-type transistor Tr_7 having its emitter directly connected to the power source terminal 6b, its collector con-

nected to the power source terminal 6a through a collector load resistor and its base connected to the emitter of, for example, the aforementioned transistor Tr_6 (or the collector of the transistor Tr_4) at least through a Zener diode Z_D .

Accordingly, the transistor Tr_7 is adapted to be in the on state when the level of the signal S_5' exceeds the sum E_4 (FIG. 2D') of the Zener voltage of the Zener diode Z_D and the forward drop voltage between the base and emitter of the transistor Tr_7 , and to be in the off state when the level of the signal S_5' becomes lower than the sum of the voltages. As a result of this, the pulse width modulator circuit 7 produces a rectangular wave comparison signal S_6 such as depicted in FIG. 2E which has been modulated in pulse width in accordance with the peak value of the triangular wave signal S_5 .

With the above arrangement, the frequency, which is capable of feeding a sawtooth pulse S_3 of a peak amplitude permitting the start of the pulse width modulating action of the pulse width modulator circuit, that is, the frequency of the output signal S_1 of the signal generator 1 can be determined dependent upon the reference DC voltage E fed to the base of the transistor Tr_5 of the differential amplifier circuit. In addition, the reference value, that is, the revolving number of the motor is established according to the Zener voltage of the Zener diode Z_D of the pulse width modulator circuit 7 and the forward drop voltage between the base and emitter of the transistor Tr_7 , and an emitter-follower type transistor circuit is interposed as a buffer between the differential amplifier circuit and the pulse width modulator circuit so as to insure sufficient switching action of the pulse width modulator circuit.

The reason why the reference value is thus established in two stages is to improve the servo control sensitivity by sharpening the rise of the signal fed to an integration circuit 8 described later when the revolving number of the motor varies in excess of the set value.

Namely, the signal S_5 or S_5' derived from the comparator circuit 5 is a triangular wave whose height and base vary, so that the rise of the signal S_5 or S_5' not so sharp and this presents a problem especially when accurate servo is required. To settle the problem, in the present example the signal S_5 or S_5' is converted by the pulse width modulator circuit into a pulse-width-modulated wave S_6 the peak value of which is constant and only the pulse width of which varies with changes in that of the signal S_5 or S_5' and accordingly the base thereof.

Consequently, since the peak value of the signal S_6 at the rise thereof becomes the same as those of the subsequent pulses, the rise of the signal can be rendered sharp and the ripple factor of the value integrated by the integration circuit 8 described later can be reduced by selecting the Zener voltage of the Zener diode so as to approximate the pulse width of the pulse-width-modulated wave signal to the base length of the triangular wave. If the same ripple factor is permissible, the integration time constant can be decreased to provide for enhanced followup property in servo control.

The rise and fall of the waveform of the signal S_6 can be improved by connecting the collector of the transistor Tr_7 through the resistor R_6 to the base of the transistor Tr_4 as shown and by positively feeding the rectangular wave comparison signal S_6 from the transistor Tr_6 back to the stage preceding it.

The rectangular wave comparison signal S_6 is applied to a low-pass filter, that is, the integration circuit 8 consisting of a resistor R_5 and a capacitor C_2 to provide a DC voltage signal such as shown in FIG. 2F which corresponds to the pulse width of the rectangular wave comparison signal S_6 , that is, a demodulated signal S_7 of the frequency-modulated signal S_1 derived from the signal generator 1, shown in FIG. 2A. The demodulated signal S_7 is fed to a DC amplifier 9 consisting of transistors Tr_8 and Tr_9 . The motor M is connected, for example, between the collector of an output transistor Tr_9 of the DC amplifier 9 and the power source terminal 6a and is supplied with a current depending upon the level of the DC voltage signal S_7 fed to the DC amplifier 9.

With the above arrangement, an increase in the revolving speed of the motor M causes an increase in the frequency of the frequency-modulated signal S_1 derived from the signal generator 1 thereby to shorten the period of the differentiated pulse S_3 , that is, the repeating cycle of the sawtooth wave signal S_3 . This leads to a decrease in the peak value of the sawtooth wave signal S_5 , by which the pulse width of the rectangular wave comparison signal S_6 is decreased to lower the level of the DC voltage S_7 applied to the DC amplifier 9. As a result of this, the collector current of the output transistor Tr_9 , that is, the current flowing to the motor M decreases to reduce its speed. While, a decrease in the revolving speed of the motor M causes an increase in the current fed to the motor M to increase its speed. Accordingly, self-start of the motor M is possible and its revolving speed is always controlled to be constant.

With the above-described speed control system of this invention, stable and highly sensitive control can be achieved and since the inclination of the sawtooth wave signal S_3 is rendered variable, the reference speed of the rotary member, that is, the motor M in the illustrated example can be selected over a wide range.

Even if the revolving number of the motor is invariable, the frequency-modulated signal S_1 is often slightly amplitude-modulated, as indicated by a broken line S_1' in FIG. 2A, by a displacement of the signal generator unit between the magnetic center of the rotor and that of the stator which is caused by a change in thrust in the axial direction of the motor shaft.

Accordingly, where the rectangular wave signal S_2 has been produced by shaping the waveform of the signal S_1 as above described, there is the possibility that the pulse width of the signal varies even if the frequency of the signal S_1 is invariable. Provided that the period of the signal S_2 , for example, at its rising portion agrees with that of the frequency-modulated signal S_1 , the period of the signal S_2 at the falling portion does not agree with that of the signal S_1 . Consequently, when a servo signal (the signal S_8 in FIG. 2) is produced by using both the rise and fall of the signal S_2 , an error is introduced to make it impossible to obtain accurate comparison output, and in the case of controlling the revolution of a motor the established revolving number of the motor is caused to vary.

With the rotary member speed control system of the present invention, however, the frequency-modulated signal S_1 , which is generated in relation to the revolution of the rotary member, that is, the motor in the illustrated example, is shaped in waveform to produce the rectangular wave signals S_2 , and the sawtooth wave generator 4 is driven by either one of the differentiated pulses S_3 and S_4 of the signal S_2 at its rise and fall, that is, by the differentiated pulse S_3 only in the illustrated example, thereby producing one sawtooth wave signal S_5 , that is, one rectangular wave comparison signal S_6 every one cycle of the frequency-modulated signal S_1 . Consequently, even if the frequency-modulated signal S_1 is amplitude-modulated to vary the differentiated pulse, for example, S_4 , there is no possibility that the variation in the pulse S_4 appears as an error component. Thus, the speed control system of this invention is extremely high in precision and accordingly it ensures stable control of the motor which is not affected by the influence of the variations in the thrust of the motor shaft and so on.

As previously described, the reference speed of the motor M depends upon the inclination of the sawtooth wave signal S_5 , the sum E_1 of the emitter voltages of the transistors Tr_4 and Tr_5 and the forward drop voltage between the base and emitter of the transistor Tr_4 and the sum E_2 of the Zener voltage of the Zener diode Z_D and the forward drop voltage between the base and emitter of the transistor Tr_7 . In the present invention, however, means for changing the inclination of the sawtooth wave signal S_5 , that is, the means for changing the time constant for charge of the signal S_5 is provided, so that the reference speed of the motor M can be selected at will over a wide range by changing over the switch 75 S as illustrated to select the resistors R_{10} , R_{20} and R_{30} .

Further, since the currents and voltages in the overall control system vary in an intermittent manner, heat generation is low and hence the device for the speed control system can be readily produced in the form of an integrated circuit.

In FIG. 3 there is illustrated another embodiment of this invention which is identical in fundamental circuit construction with the example of FIG. 1, and accordingly elements similar to those in FIG. 1 are identified by the same reference numerals and no further detailed description will be repeated. The circuit of this example is simpler in construction than that of FIG. 1 in constituting the sawtooth wave generator 4 with one transistor Tr_2 and in elimination of the emitter-follower type transistor amplifier consisting of the transistor Tr_8 and the Zener diode Z_D in FIG. 1. The Zener diode Z_D is incorporated to stabilize the power source voltage.

The present example is similar in the fundamental operation to that of FIG. 1. In FIG. 4 waveforms corresponding to those in FIG. 2 are designated with the same reference numerals. A sawtooth wave signal S_5 such as shown in FIG. 4D, which is derived from a sawtooth base generator 4, is applied to the base of a transistor Tr_4 of a differential Zener consisting of transistors Tr_{4D} and Tr_5 of a comparator circuit 5 and the signal S_5 is compared with the sum E_1 of the emitter voltages of the transistors Tr_4 and Tr_5 and a forward drop voltage between the base and emitter of the transistor Tr_4 as in the case of FIG. 1 to generate in the collector of the transistor Tr_4 a signal S_5' depicted in FIG. 4D', thereby producing in the base of a transistor Tr_7 a signal S_5'' shown in FIG. 4D''. The resulting signal S_5'' is compared with a forward drop voltage E_2' between the base and emitter of the transistor Tr_7 to produce in the collector of the transistor Tr_7 a rectangular wave comparison signal S_6 shown in FIG. 4E. The subsequent operations are the same as those in the example of FIG. 1.

Also in the example of FIG. 3 stable and highly sensitive control can be achieved and the reference speed of a motor M can be freely selected over a wide range by changing the inclination of the sawtooth wave signal S_5 by changing over a switch S as in the case of FIG. 1.

Although, in the foregoing, the sawtooth wave signal S_5 derived from the sawtooth wave generator 4 is fed to the comparator circuit 5 and the rectangular wave comparison signal S_6 resulting from comparing the signal S_5 with the reference DC voltage is applied to the integration circuit 8, it is also possible to apply the sawtooth wave signal from the sawtooth wave generator 4 to the integration circuit and to apply the output of the integration circuit to the comparator circuit to be compared with reference DC voltage.

While the present invention has been described in connection with the case where a signal, frequency-modulated in accordance with the rotational angular velocity of the motor M, is derived from the signal generator 1 mounted on the rotary shaft of the motor M and is demodulated to control the revolving speed of the motor M, the frequency-modulated signal may be produced by other methods. Further, the present invention is suitable for use in speed control of rotary members

such as a motor, a capstan and the like of magnetic recording and reproducing devices and so on which is achieved by controlling a brake mounted on a rotary shaft of the rotary member.

5 It will be apparent that many modifications and variations may be effected without departing from the scope of the novel concepts of this invention.

I claim as my invention:

1. A speed system for a rotary member comprising means 10 for generating a sine wave signal that is frequency-modulated in accordance with the rotational speed of said rotary member, means for producing a sawtooth wave signal for each complete cycle of said frequency-modulated sine wave signal with the pitch of each said sawtooth wave signal, and hence 15 the peak voltage thereof, corresponding to the period of the respective cycle of said frequency-modulated signal, means for comparing said peak voltage of each sawtooth wave signal with a reference voltage and for producing a comparison signal in response to said peak voltage being in excess of said reference voltage with said comparison signal corresponding to the extent of said excess, means responsive to said comparison signal for providing a corresponding control signal, means for exerting a driving force on the rotary member in accordance with said control signal, and means for varying the 20 inclination of said sawtooth wave signal and thereby determining the speed of the rotary member which is to be maintained in correspondence to said reference voltage.
2. A speed control system according to claim 10, wherein said rotary member is a DC motor.
3. A speed control system according to claim 1, wherein said rotary member is a capstan.
4. A speed control system according to claim 1, wherein said means for producing a sawtooth wave signal includes shaping circuit means shaping said frequency-modulated signal to provide a rectangular wave having a pitch corresponding to the period of said frequency-modulated sine wave, differentiating circuit means differentiating said rectangular wave to provide sets of differentiated pulses at the rise and fall, respectively, of said rectangular wave, and sawtooth 35 wave generating means triggered by one of said sets of differentiated pulses.
5. A speed control system according to claim 1, wherein said means for providing the control signal further includes pulse width modulating circuit means providing a wave which is pulse width modulated in accordance with said comparison signal.
6. A speed control system according to claim 5, wherein said pulse width modulating circuit means provides said wave only when said comparison signal exceeds a predetermined level.
7. A speed control system according to claim 6, wherein said means for providing the control signal further includes integration circuit means integrating the pulse width modulated wave to provide said control signal in the form of a varying L C voltage.
